Primary Examiner — Christian P. Mclean*Assistant Examiner* — Kaitlan Walker*(74) Attorney, Agent, or Firm* — B. Craig Killough(57) **CLAIM**

The ornamental design for a waterfowl decoy holder as shown and described.

DESCRIPTION

FIG. 1 is a top perspective view of a waterfowl decoy holder showing the new design;

FIG. 2 is a front elevation of the waterfowl decoy holder; FIG. 3 is a rear elevation of the waterfowl decoy holder; FIG. 4 is a right side elevation of the waterfowl decoy holder;

FIG. 5 is a left side elevation of the waterfowl decoy holder; FIG. 6 is a top plan view of the waterfowl decoy holder; FIG. 7 is a bottom plan view of the waterfowl decoy holder; and,

FIG. 8 is another perspective view of the waterfowl decoy holder shown in a use configuration with a waterfowl decoy. The broken lines in the drawings depict both portions and environmental structure that form no part of the claimed design.
